T. W. BURLEY

INTERLOCKING APPARATUS FOR RAILROAD SIGNALS AND SWITCHES.

No. 398,766.

Patented Feb. 16, 1889

UNITED STATES PATENT OFFICE.

THOMAS W. BURLEY, OF LONG ISLAND CITY, NEW YORK.

INTERLOCKING APPARATUS FOR RAILROAD SIGNALS AND SWITCHES.

SPECIFICATION forming part of Letters Patent No. 398,766, dated February 26, 1889.

Application filed May 28, 1888. Serial No. 275,266. (No model.)

To all whom it may concern:

Be it known that I, THOMAS WILLIAM BURLEY, of Long Island City, in the county of Queens and State of New York, have invented 5 an Improvement in Interlocking Apparatus for Railroad Signals and Switches; and the following is declared to be a full and complete description of the same.

In modern and improved railway systems 10 it is usual to employ at intersections and branches of a road systems of switches and signals for the management and protection of trains. This becomes necessary and essential to prevent accidents occurring and 15 loss of life, and these devices as heretofore employed have consisted in series of levers grouped together at a common point and operated from that point for setting the signals and moving the switches, and thus controlling 20 the movements of incoming and outgoing trains.

The object of my invention is to prevent the setting of signals before the setting of the switches, and to so interlock the signals when 25 set that the switch must be reset before the signals can be returned to a normal position.

My improvement consists in the combination, with the usual pivoted lever operated by hand and the mechanism connecting the 30 same to a switch or distant signal, of pivoted segments and locking-bars connected therewith, which bars move through the frame of the lock-box and operate the devices, herein-after described, by which such bars and segments, as well as the operating-levers, are 35 locked or unlocked in series, the interlocking bars being actuated either by the pivoted lever alone operated by the hand, or by the pivoted lever and pivoted segment operated 40 by the hand and foot.

In the drawings, Figure 1 is a side elevation of my improved interlocking device. Fig. 2 is an elevation of one end of the same. Fig. 3 is a separate elevation, in larger size, 45 of the lock-box frame and interlocking levers in their normal position; and Fig. 4 is a similar view with the parts locked.

The lever *a* is of the usual character employed in similar interlocking mechanism, and 50 the same is pivoted at its lower end in the frame *A*, which end of this L-shaped lever has connected to it a rod, *A*², or other device

running to a switch or distant signal, and the lever *a* also passes through the frame portion *A'*, which may represent the floor of the signal-station. Connected to this floor *A'* are 55 the segments *b*, and there is one of these segments *b* for each one of the levers *a*, and there is a pivot at 1 upon a bracket fastened to the frame or upon one segment *b*, to which the 60 swinging lever-segment *d* is pivoted, and upon one side of the segment *d* is a rib or flange, *d'*. Connected to the lever *a* is a pivoted handle, *a'*, rod *c*, spring *c'*, and upon the end of the rod *c* is a slotted bolt, *c*², the rod *c* passing 65 through the frame *c*³ upon the lever *a*, and the spring *c'* surrounding the rod *c* and located between the opposite ends of the frame *c*³, the slotted end of the bolt *c*² passing around the flange *d'* of the segment *d*, and there are 70 notches at 2 in the segment *b* adapted to receive the end of the slotted bolt *c*². In either extreme position of the lever *a* the spring *c'* presses the slotted bolt *c*² down into either 75 notch 2, and as the upper edge of the slotted bolt is over and bears against the top edge of the flange *d'* the action of the spring *c'* will thus move the segment *d* down at either end.

B represents the lock-box frame, and the same is connected to and supported upon the 80 frame *A'* and set at an inclination, preferably as shown in Fig. 1, and passing vertically through said lock-box frame are locking-bars *e* *e'*, and passing horizontally through said frame *B*, between the ribs thereof, are the sliding bars 85 *f* *f'* *f*², and pivotally connected with each of the locking-bars at their lower ends, *e* *e'*, is a swinging segment, *d*, pivoted to a segment *b* and associated with the lever *a*, and I prefer to group the segments and levers in series of 90 four, as shown in Figs. 3 and 4 of the drawings, these devices forming the operating and holding mechanisms for a switch and the signals that govern the same.

Upon the locking-bar *e*, Fig. 3, I rivet an 95 inclined rib, *h'*, and upon the sliding bar *f*, I rivet the beveled lugs *h* and the dogs *i*, and the bevel-ended bolt-bars *k* *k'* rest upon the sliding bar *f*² and in the position shown in Fig. 3, wherein the locking-bars *e* *e'* are marked "Distant," "Main," "Detection," and "Switch." These bolt-bars *k* are shown with their beveled ends engaging notches in the distant and 100 detection bars *e'*.

B, set at a slight inclination from the vertical line, the locking-bars $e e'$, moving up through the same, the horizontal sliding bars $f f' f^2$, the beveled lugs h upon the upper face of the bars f , the ribs h' upon the bars e , and dogs i upon the bars f and adapted to engage notches in the bars e' , and mechanism, substantially as specified, for operating the bars $e e'$, substantially as set forth.

2. The combination, in an interlocking apparatus, with the pivoted levers a and the frame to which the same are connected, of the lock-box frame B, set at a slight inclination from the vertical line, the locking-bars $e e'$, moving up through the same, the horizontal sliding bars $f f' f^2$, the beveled lugs h , ribs h' , and dogs i , the bolt-bars $k k'$, the interlocking bars $l l' l^2 l^3$, and the interlocking bolts $m m' m^2$, and mechanism, substantially as specified, for operating the bars $e e'$, substantially as set forth.

3. The combination, in an interlocking apparatus, with the pivoted levers a and the frame to which the same are connected, of the lock-box frame B, set at a slight inclination from the vertical line, the locking-bars $e e'$, moving up through the same, and the horizontal sliding bars $f f' f^2$, moving through the grooves of the same, the interlocking bars $l l' l^2 l^3$, connected upon the faces of the bars e' and notched at convenient places, the interlocking bolts $m m' m^2$, riveted upon one of the sliding bars f' , and having beveled ele-

vated ends passing over the edges of the bars $e e'$ and engaging with the notches or with the edges of the interlocking bars $l l' l^2 l^3$, and mechanism, substantially as specified, for operating the parts, substantially as set forth.

4. The combination, in an interlocking apparatus, with the lock-box frame, the sliding bars passing through the grooves thereof, and the locking-bars $e e'$, passing across through said frame, of beveled lugs h upon one or more of the sliding bars f , the ribs h' on one or more of the locking-bars, the pivoted swinging ribbed segments d , to the slotted ends of which the lower ends of the locking-bars are directly pivoted, and mechanism, substantially as specified, for moving one of the locking-bars, and by said rib h' shifting the sliding bars, substantially as set forth.

5. The combination, in an interlocking apparatus, with the pivoted levers a and the frame to which the same are connected, of the lock-box frame B, the locking-bars $e e'$, moving up through the same, the horizontal sliding bars $f f' f^2$, the interlocking bars $l l' l^2 l^3$, and the interlocking bolts $m m' m^2$, and mechanism, substantially as specified, for operating the locking and sliding bars, substantially as set forth.

Signed by me this 22d day of May, A. D. 1888.
T. W. BURLEY.
